UNITED STATES PATENT OFFICE.

HENRY G. LANE AND HARRY STANFORD WILLIAMS, OF SAN DIEGO, CALIFORNIA.

ELECTRIC SIGN.

1,186,916.

Specification of Letters Patent. Patented June 13, 1916.

Application filed June 30, 1915. Serial No. 37,274.

To all whom it may concern:

Be it known that we, HENRY G. LANE and HARRY STANFORD WILLIAMS, citizens of the United States, residing at San Diego, in the county of San Diego and State of California, have invented certain new and useful Improvements in Electric Signs; and we do declare the following to be a full, clear, and exact description of the invention, such as will enable others skilled in the art to which it appertains to make and use the same.

Our invention relates to useful improvements in electric signs and more particularly to those of the indirect radiation type employing a plurality of reflectors for intensifying light rays projected from a source of light within a housing, through openings arranged in the face plate of said housing corresponding with the shapes of a number of characters.

The object of the invention is to provide a sign of this class having improved means for detachably securing the reflectors thereof in position, such means serving also to retain in position a plurality of transparent lens plates which prevent dust and the like from entering the casing through the openings therein.

With this general object in view, the invention resides in certain novel features of construction and in unique combinations of parts to be hereinafter fully described and claimed, the descriptive matter being supplemented by the accompanying drawing which constitutes a part of the application and in which;

Figure 1 is a face view of a sign constructed in accordance with the invention; Fig. 2 is a vertical section thereof as seen along the plane indicated by the line 2—2 of Fig. 1; Fig. 3 is a rear elevation of a portion of the face plate and one of the reflectors carried thereby; Fig. 4 is a vertical section taken on the plane designated by the line 4—4 of Fig. 3; Fig. 5 is a view similar to Fig. 3 disclosing the application to use of a supplemental reflector; Fig. 6 is a vertical section of Fig. 5 taken on the plane indicated by the line 6—6. Fig. 7 is a front elevation of a portion of the sign constructed as disclosed in Figs. 5 and 6.

In these drawings, similar reference characters designate corresponding parts throughout the several views, C designating

broadly an appropriate casing or sign box 55 having a face plate P provided with a number of preferably circular openings O so disposed as to represent one or more letters, numerals, or other characters. Disposed within the casing C and preferably adjacent the lower side thereof, is a pair of electric lights L whose rays are to be reflected through the openings O to illuminate the sign, the radiation of such rays being facilitated by the reflectors 1 shown in Figs. 1 to 4 inclusive, or by those indicated at 1^a and 1^b in Figs. 5, 6 and 7. Each reflector 1 is here shown in the form of a metal disk having in one of its edges a slot 2 which constitutes an eye, while at its opposite edge and preferably formed integrally therewith, each reflector 1 is equipped with an arm 3 whose free end is bent to form a hook 4.

Coating with the eyes 2, is a plurality of hooks 5 which are here shown as disposed at the upper sides of the openings O and as formed of tongues left projecting into said openings when the same are formed in the face plate. As clearly shown in Figs. 3 and 4, the eyes 2 receive therein the hooks 5 when the reflectors are to be applied to use, while the hooks 4 are received in eyes 6 formed in rearwardly extending tongues which are likewise left extending into the openings O when the latter are formed. By this manner of attaching the reflectors, it will be evident that although they may be quickly and easily applied, they will be reliably held in correct position. Furthermore, the attaching means is so simple as to allow unskilled laborers to correctly position the reflectors with respect to the numerous openings.

In most cases, it becomes expedient to space the lower edges of the reflectors at the upper side of the casing, greater distances from the face plate than the lower edges of those at the lower side thereof, whereby to prevent shadows from being cast on the uppermost reflectors by the lowermost. In order to accomplish this end, the arms 3 are constructed of various lengths as clearly disclosed in Fig. 2 whereby, when applying the reflectors, by simply passing the eyes 2 over the hooks 5, and snapping the hooks 4 in the eyes 6 such reflectors will be properly positioned at the correct angle to the face plate without making any adjustments whatso-

ever. In most cases, it becomes expedient to provide a transparent closure for the several openings O to prevent the entrance of dust and the like, and although such closures might well be in a number of forms, they are preferably embodied as shown in the drawings in which is depicted a plurality of transparent plates 7 of circular contour, said plates being constructed of glass, mica, celluloid or any other appropriate transparent material. At diametrically opposite points, the plates 7 are provided with slots 8 in their edge portions receiving therein the hooks 5 and the tongues in which the eyes 6 are formed. By this arrangement, when the reflectors 1 are properly positioned, the lens plates will be reliably held against dislocation, it being thus evident that although the construction is exceedingly simple, it will be highly efficient.

In Figs. 5, 6 and 7, a pair of hooks 5^a and 5^b is shown disposed at diametrically opposite points adjacent the edge of the opening O in the plate P, such hooks being passed through eyes 6^a and 6^b in a frusto-conical reflector 1^a which is preferably corrugated circumferentially, the opening O being closed, in these figures, by an appropriate lens 9 having a circular enlargement 10 which closely abuts the wall of the opening O, and a flange 11 which is interposed between the inner side of the plate P and the reflector 1^a. The rear contracted end of the reflector 1^a is provided on one of its sides 35 with a hook 5^c and at a diametrically opposite point with an eye 6^c the former being received in an eye 2^c on the upper edge of a reflector 1^b similar to the reflectors 1 previously described, said reflector 1^b having on its lower edge a laterally extending arm 3^a having its terminal bent to form a hook 4^a received by the eye 6^c. The only difference between the reflectors 1 and 1^b is that the latter are preferably provided with parallel corrugations to intensify the light rays reflected therefrom.

The active faces of all of the reflectors are to be silver or nickel-plated, and the inner side of the casing C will be preferably 50 painted a light color, these provisions being obviously made to increase materially the brilliancy of the rays projected from the sign.

From the foregoing description, taken in connection with the accompanying drawings, it will be evident that although comparatively simple and inexpensive construction has been provided for the attainment of the desired results, the invention will be 55 highly efficient and durable and will possess a number of advantageous characteristics.

In the drawing, certain specific details of construction have been illustrated and in the preceding we have rather specifically described such details, but it is to be understood

that we need not be restricted thereto otherwise than to the extent to which the appended claims limit us.

We claim:

1. The combination with the face plate of a sign box having a light passage therethrough, of a hook contiguous to the upper side of said passage and extending upwardly therefrom, and a reflector having an opening formed through its upper edge portion and snugly receiving said hook therein.

2. The combination with the face plate of a sign box having a light passage therethrough, of an obliquely disposed reflector in rear of said passage, and interengaging hooks and eyes carried by the face plate and reflector and securing opposite edges of said reflector to said face plate.

3. The combination with the face plate of a sign box having a light passage therethrough, of a hook contiguous to one side of said passage, an eye adjacent the opposite side thereof, a reflector in rear of said passage having an eye at one edge receiving the aforesaid hook, and a hook on the opposite edge of said reflector received by the first named eye.

4. The combination with the face plate of a sign box having a light passage therethrough, of a hook contiguous to one side of said passage, an eye adjacent the opposite side thereof, an obliquely disposed reflector in rear of the passage having an eye at one edge receiving the aforesaid hook therein, and an arm extending laterally from the opposite edge of said reflector and having at its free end a hook received by the first named eye.

5. The combination with the face plate of a sign box having a light passage therethrough, of a hook contiguous to one side of said passage, an eye adjacent the opposite side thereof, an obliquely disposed disk-like reflector in rear of the passage and having in one edge an opening forming an eye receiving therein the aforesaid hook, and an arm formed integrally with the opposite edge of said reflector, extending laterally therefrom toward the face plate and having its free end formed into a hook received in the first named eye.

6. The combination with the face plate of a sign box having a light passage therethrough, of a hook adjacent one side of said passage and extending rearwardly therefrom, a transparent plate having an opening through which the hook passes, and a reflector in rear of the transparent plate having an eye receiving the hook therein.

7. The combination with the face plate of a sign box having a light passage therethrough, of a hook adjacent one side of said passage and extending rearwardly therefrom, an eye adjacent the opposite side of the passage and likewise extending rear-

wardly therefrom, a transparent plate having openings through which the hook and eye project, an obliquely disposed reflector in rear of the transparent plate and having 5 at one edge an eye receiving the hook, and an arm projecting laterally from the opposite edge of said reflector toward the transparent plate and having its free end shaped to form a hook received in the first named

10 eye.

8. The combination with the upright face plate of a sign box having a light passage therethrough, of a hook adjacent and extending upwardly from the upper side of 15 said passage, an inclined reflector in rear of the face plate having in its upper edge an eye receiving the hook therein, and a spacing arm joined to the reflector and extending from the lower edge thereof toward 20 the face plate.

9. The combination with the upright face plate of a sign box having a light passage therethrough, of an inclined reflector in rear of said passage and having its upper edge 25 disposed contiguous to the face plate, a hook and eye connection between said upper edge of the reflector and the face plate, and an arm joined permanently to the reflector and extending from the lower edge thereof toward 30 the face plate to space said reflector from said plate.

10. The combination with the upright face plate of a sign box having a light passage

therethrough, of an inclined reflector in rear of the passage and having its upper edge 35 disposed contiguous to the face plate, a detachable connection between said upper edge of the reflector and the face plate, a spacing arm extending from the lower edge of said reflector toward the face plate, and 40 an additional detachable connection between said arm and the face plate.

11. The combination with a sign box having therein a source of light and provided with a face plate having an alined series 45 of light passages therethrough, of hooks projecting inwardly contiguous to the sides of the passages remote from the source of light, eyes contiguous to the opposite sides of said 50 passages, oblique reflectors in rear of the passages and disposed at various angles in respect to the face plate, said reflectors having in one edge eyes which receive the aforesaid hooks, spacing arms at various lengths 55 projecting one from the opposite edge of each reflector, and hooks on the free ends of said arms received in the first named eyes.

In testimony whereof we have hereunto set our hands in presence of two subscribing witnesses.
